RIP STRIP KEY AND ATTACHING MEANS
FOR CONTAINERSWilliam F. Punte, Syracuse, N. Y., assignor to
Continental Can Company, Inc., New York,
N. Y., a corporation of New York

Application March 18, 1933, Serial No. 661,596

2 Claims. (Cl. 220—52)

The invention has to do with new and useful improvements in an implement for opening a container, such as a key for removing the tearing strip thereof, and more particularly to the means for attaching the implement to the container so that it may be secured thereto and marketed therewith and easily removed from the container for opening the same.

An object of the invention is to provide an attaching means for an implement of the above type which is shaped so as to have a firm but yielding grip on a portion of the container, permitting the implement to be sprung into engagement with the container and to be forcibly released therefrom.

A further object of the invention is to provide an attaching means for an implement for opening a container which permits the implement to yieldingly grip the container at opposite sides of and beneath the double seam securing the container end to the container body.

A still further object of the invention is to provide a key opening implement with an attaching means of the above type wherein the spring of the metal in the shank portion of the key maintains the yielding contact between the key and the members of the container gripped thereby.

In the drawing—

Figure 1 is a plan view of a container showing a key provided with the improved attaching means, with the key positioned to be sprung into engagement with the container;

Fig. 2 is a similar view, but showing the key as sprung into attachment with the container;

Fig. 3 is a side view of the container with the key parts as positioned in Fig. 1;

Fig. 4 is a view similar to Fig. 3, but showing the key as attached to the container;

Fig. 5 is a sectional view on the line 5—5 of Fig. 4;

Fig. 6 is a sectional view on the line 6—6 of Fig. 2, and

Fig. 7 is a sectional view similar to Fig. 5, but showing the key as attached to the straight wall of a square container.

The invention as illustrated in the drawing is embodied in a key for removing a tearing strip. It will be understood, however, that other types of opening implements may be used and attached to the container by the novel attaching means

embodying applicant's invention. The key is preferably formed from a resilient wire which is bent upon itself to produce a shank portion having the members thereof spaced to form a slot adapted to receive the tongue of the tearing strip, so that the tearing strip may be wound on to the shank of the key and the metal ruptured thereby. The shank portions midway thereof are bent laterally away from each other, and thence out of the plane of the shank, so as to provide two spaced gripping points which are adapted to engage one member of the container. As shown, these gripping points engage the gripping wall forming the depression in the container end, or what might be termed the inner side of the double seam. These members having the gripping points extend out over the double seam, and are thence bent downwardly and toward each other so that they substantially meet at a line centrally of the shank when the key is completed and before it is attached to the container. It is the ends of these members projecting toward each other that provide the gripping points for contacting with the container wall outside of and beneath the double seam.

These members having the gripping points extend out over the double seam, and are thence bent downwardly and toward each other so that they substantially meet at a line centrally of the shank when the key is completed and before it is attached to the container. It is the ends of these members projecting toward each other that provide the gripping points for contacting with the container wall outside of and beneath the double seam.

This provides a key attaching means wherein there are spaced gripping points adapted to engage one member of the container, and that is, the inner wall of the double seam, while there are spaced points located intermediate these first-named gripping points which contact with the other member of the container, that is, the outer wall hereof just beneath the double seam. The gripping points contacting with the inner member lie in a plane which is spaced from the plane containing the intermediate gripping points a less distance than similar planes containing the points of contact on the container made by these gripping points of the key.

In order, therefore, to bring these contact points into engagement with the container, it is necessary to spring the shank of the key. The resilience, therefore, of the members forming the key will continuously cause these gripping points to firmly grip the container.

Referring more in detail to the drawing, a container is shown which includes a body portion 1 and an end portion 2 which is secured thereto by a double seam 3 which is of the usual type. The container end 2 has a central depression forming a vertical wall 4 which may be said to be the

inner wall of the double seam. The body wall is provided with score lines 5, 5 setting off the tearing strip 6 having a tongue 7. This tearing strip is of the usual construction and further description thereof is not thought necessary. The implement for opening this type of container has been termed a key, and as shown in the drawing, this opening key consists of a resilient wire bent upon itself to form shank members 8 and 9 which are spaced from each other so as to provide a slot 10. This slot is slipped over the tongue 7 and then the tongue is rolled on to the shank, and the tearing strip thus ruptured. The shank 9 is bent laterally as indicated at 11, while the shank 8 is bent laterally as indicated at 12. The outer end of the shank portion 11 is bent upwardly forming a gripping point 13 which is adapted to engage the vertical wall 4 of the container, that is, the inside of the double seam. The shank 12 is provided with a similar upwardly bent portion having a gripping point 14. These gripping points 13 and 14 are spaced from each other, and are the two gripping points which engage the inner member of the container when the key is attached thereto.

The upstanding member carrying the gripping point 13 is extended over the double seam as indicated at 15, and is thence bent downwardly as indicated at 19, and inwardly toward the center 30 of the shank as indicated at 20. These portions 11, 12, 13, 18, 17 and 20 form a handle portion for the key when it is detached to aid in turning the key for winding the tearing strip thereon. As clearly shown in Fig. 1, the ends of the members 35 17 and 20 are normally close together, and they may be separated by the springing of one shank member 8 away from the other shank member 9. The member 17 is adapted to grip the container at the point 17^a, while the member 20 grips the 40 container at the point 20^a (see Fig. 2). The vertical plane containing the gripping points 13 and 14 is spaced such a distance from the vertical plane containing the points 17^a and 20^a, before the key is attached, that the arc of a circle passing through all of these points is less than the 45 arc of the circle forming the double seam. In order, therefore, to bring the key into gripping engagement with the double seam, the shank members 8 and 9 of the key must be separated so as to 50 separate the points 13 and 14. In order to accomplish this, the key is preferably placed on the container with one of the shank members contacting with the double seam. As shown in Figures 1 and 3, the member 18 is in contact with 55 the double seam; the gripping point 14 engaging the inner wall thereof, and the gripping point 20^a contacting with the lower portion of the double seam. The operator then places a finger on the portion 15 of the shank member 9 and forces it 60 away from the shank member 8 so as to spring the contact member 13 downwardly inside of the double seam. This brings the key to the position shown in Figures 2 and 4 to 6, inclusive. This springing of the key on to the container separates 65 the shank members, as noted, and the tendency of the shank members to spring back into the normal position shown in Fig. 1, causes a firm gripping of the points of contact of the key with the container. The points of contact with the 70 container are at 13 and 14 on the inside of the double seam, and 17^a and 20^a on the outside of the double seam. There is also a certain spring in the member 17 and in the member 20, and likewise in the members 15 and 18, all of which 75 are put under strain when the key is placed on

the container, and thus it is that the resiliency of the entire key is made available to bring about a firm gripping contact between the key and the container. The members 17 and 20, when the key is attached to the container, lie beneath the double seam, and this aids in a very firm engagement of the key with the container. In order to remove the key, the operator pushing laterally and upwardly on the shank members 8 and 9, may forcibly release the contact point 13 or 14 from the container. The key may be readily sprung on by hand after the container is closed, or by machinery, and will be firmly retained on the container and is marketed therewith. The shank of the key lies housed within the recess in the container end, and the only portions extending above the double seam of the container are the parts 15 and 18.

In Fig. 7 of the drawing, the key is shown as applied to a container having a straight side wall, wherein the straight double seam is indicated at 21. The key attaching means is of the same construction as that described above, with the members 17 and 20 placed initially so that they incline inwardly toward the shank of the key, and it is 100 the spring of these members that grips the container beneath the double seam for holding the key firmly attached thereto.

It will be noted that the gripping points in applicant's key attaching means which contact with 105 one of the gripping members, that is, the inner wall of the container, are spaced from each other, while the gripping points contacting with the other member of the container are disposed intermediate the same. In other words, the gripping 110 points are not opposed to each other radially of the container, and this gives a much greater stretch of metal between the gripping points and a better resilient gripping engagement of the contact points with the container.

While there has been described in detail a shaping of the key for the attaching of the same to spaced members on the container which are at the inner and outer sides of the double seam, it will be understood that the key may be attached to spaced 120 members otherwise disposed on the container end. The essential feature of the invention is the placing of the gripping points relative to the members with which they contact so as to get this firm gripping engagement which may be secured when 125 the opposed gripping points are, as described, out of radial alinement.

While the invention has been described in detail as applied to a key adapted to be attached to a tearing strip, it is equally applicable to any type 130 of container opening device which is marketed with the container, and detached therefrom for opening the container.

Having thus described the invention, what I claim as new and desire to secure by Letters Patent is:—

1. The combination of a container having a tearing strip, a key adapted to engage said tearing strip, said key being of spring wire bent upon itself to form a shank and a handle portion, said handle portion being constructed so as to provide spaced members extending at right angles to the plane of the shank for contacting with a wall on the container, and members projecting toward each other from said spaced members, said last-named members being separated for independent yielding contact with a wall of the container at their adjacent ends.

2. The combination of a container having a tearing strip, a key adapted to engage said tearing

strip, said key being of spring wire bent upon itself to form a shank and a handle portion, said handle portion being constructed so as to provide members extending at right angles to the plane of the shank and having contacting points adapted to engage the inner wall of the double seam of said container, said handle portion having members extending over the double seam, and members carried thereby and projecting toward each other, said last-named members being separated for independent yielding contact with the outer wall of the container at points beneath the double seam and at points intermediate the inner contacting points of the handle with the double seam. 80
